DESIGN FOR A CLOCK

Joseph Albert Thoma and Alfred George Cottet,
Piqua, Ohio

Application September 10, 1936, Serial No. 64,795

Term of patent 7 years

To whom it may concern:

Be it known that we, Joseph Albert Thoma and Alfred George Cottet, each of whom is a citizen of the United States, residing in the city of Piqua, county of Miami, and State of Ohio, have invented a new, original, and ornamental Design for a Clock, of which the following is a specification, reference being had to the accompanying drawings, forming a part thereof.

Fig. 1 is a front elevational view of a clock showing our new design;

Fig. 2 is a top plan view; and

Fig. 3 is a side elevational view of the same.
We claim:

The ornamental design for a clock substantially as shown.

JOSEPH ALBERT THOMA.
ALFRED GEORGE COTTET.
